CLAIM

The ornamental design for a smart key read head node group, as shown and described.

DESCRIPTION

FIG. 1 is a top, front and left side perspective view of a smart key read head node group showing my new design;
FIG. 2 is a top, rear and right side perspective view thereof;
FIG. 3 is a bottom, rear and right side perspective view thereof;

FIG. 4 is a front elevational view thereof;
FIG. 5 is a rear elevational view thereof;
FIG. 6 is a left side view thereof;
FIG. 7 is a right side view thereof;
FIG. 8 is a top plan view thereof; and,
FIG. 9 is a bottom plan view thereof.

The broken lines in the drawings illustrate portions of the smart key read head node group which form no part of the claimed design.
